Be it known that I, JULIUS PEGEL, a subject of the Emperor of Germany, residing at Camden, in the county of Camden and State 5 of New Jersey, have invented and produced a new and original Design for a Rug; and I do hereby declare that the photographic print accompanying this specification conveys to any one skilled in the art a clear understanding 10 of the same, and is sufficient to enable such person to use my invention.

The leading features of my design consist in a center panel ornamented in the center by the representation of a bunch of fern-leaves. 15 The top of the panel is formed of scallops and arched in the center, below which is represented a row of flowers on a scroll ground. From each of the upper corners is represented a branch or spray of leaves and flowers. The 20 whole is surrounded by an ornamental border, the bottom having a double border, as shown.

The photographic print shows only three-fourths of the design. The right-hand end, or the part not shown, is exactly like the left-hand end, that is shown.
